CLAIM

The ornamental design for a brush handle, as shown and described.

DESCRIPTION

FIG. 1 is a top right front perspective view of a brush handle showing our new design. The broken lines are for illustrative purposes only and form no part of the claimed design;

FIG. 2 is a top plan view thereof; the bottom plan view being a mirror image;

FIG. 3 is a right side elevational view thereof;

FIG. 4 is a left side elevational view thereof;

FIG. 5 is a rear elevational view thereof; and,

FIG. 6 is a front elevational view thereof.
